UNITED STATES PATENT OFFICE.

LOUDOUN CAMPBELL AND FRANK G. CAMPBELL, OF WASHINGTON,
DISTRICT OF COLUMBIA.

FIRE-ALARM BOX.

No. 820,700.

Specification of Letters Patent.

Patented May 15, 1906.

Application filed April 4, 1905. Serial No. 263,795.

To all whom it may concern:

Be it known that we, LOUDOUN CAMPBELL and FRANK G. CAMPBELL, citizens of the United States, residing at Washington, in the 5 District of Columbia, have invented certain new and useful Improvements in Fire-Alarm Boxes, of which the following is a specification.

Our invention relates to fire-alarm boxes, 10 and has for its object the provision of a device of the character described having a local alarm arranged thereon in such manner that said local alarm will be sounded simultaneously with the main alarm, thereby affording 15 protection against false alarms by making certain the detection of any one turning in such false alarms.

The invention is designed to serve substantially the same purpose as the device 20 shown in Letters Patent No. 763,042, issued June 21, 1904. The present device, however, possesses advantages not possessed by the device shown in said patent.

It has been found that many people are ignorant of the proper method of turning in an 25 alarm of fire. Efforts have been made to prevent false alarms of fire by providing local alarms at the box which served to call attention to the fact that an alarm was being 30 turned in over said box. It was found, however, that in many instances the operator of the box omitted to perform the essential act of setting the main-alarm mechanism in motion, because they supposed that the fire-alarm had been turned in when the local 35 alarm sounded upon opening the door of the main box.

To meet these conditions the present invention comprises a main alarm, a local 40 alarm, and a member controlling both of said alarms, whereby they may be sounded simultaneously and whereby the operator will be required to perform but one action in turning in an alarm.

The primary object of the erection of fire-alarm boxes is of course to transmit to fire-alarm headquarters alarms of fire when fires are discovered. To properly sound the main alarm is therefore of the utmost importance, 45 the prevention of false alarms being secondary thereto. As will be presently described, the initial movement of the operating-lever sounds the main alarm immediately, after which a spring-actuated local alarm is re-

leased and continues to sound for some time 55 after the movement of its releasing-lever has ceased.

A further object of the invention is the provision of a fire-alarm box having a local alarm resting directly upon the top of said box, said 60 local alarm comprising a spring-actuated motor adapted to be directly engaged and cut out of action by the member which controls the main alarm, thereby providing a neat, compact, and ornamental fire-alarm 65 box and enabling expensive and unreliable connections between the local-alarm and said main-alarm controlling member to be dispensed with.

A further object of the invention is the 70 provision of a frangible device containing directions for the operation of the box, said frangible device normally locking the controlling member against movement, and also of a hammer or analogous member secured 75 directly to said box in a position where it will be readily accessible at all times for the purpose of fracturing said frangible device.

A further object of the invention is the provision of improved means for locking the local-alarm casing to the main box, whereby 80 said local-alarm casing may be readily applied to boxes now in use.

A further object of the invention is the provision in a fire-alarm box of a main and local 85 alarm, a member controlling both of said alarms, a member normally tending to force the door of the fire-alarm box open, and means for cutting both of said alarms out of action when it is desired to permit an 90 inspector or other official to open said box, whereby said alarms will not at such time be sounded.

Further objects and advantages of the invention will be set forth in the detailed description which now follows.

In the accompanying drawings, Figure 1 is a perspective view of a fire-alarm box having my attachments applied thereto, showing the parts in their normal position. Fig. 2 is a 100 perspective view of a fire-alarm box having my invention applied thereto, showing the position the parts assume when the main controlling member has been actuated to open the door of the box and set the main and local alarms in operation. Fig. 3 is a vertical section of a fire-alarm box such as is shown in Fig. 1. Fig. 4 is a detail perspective view of

a hook-pulling member hereinafter described. Fig. 5 is a detail perspective view of a pin used for locking the local-alarm mechanism out of action, as will be hereinafter set forth. Fig. 6 is a horizontal section of the door of the main box and the fastening devices therefor. Fig. 7 is an elevation of the bolt shown in Fig. 6. Fig. 8 is an elevation of a portion of the local-alarm-motor frame and of the winding-key of said motor. Fig. 9 is a vertical section of a portion of the controlling-lever and of the frangible device carried thereby, illustrating the manner of locking said frangible device against removal by unauthorized persons. Fig. 10 is an elevation of a modified form of the invention, and Fig. 11 is a vertical section of a portion of the device shown in Fig. 10.

Like numerals designate similar parts in all the figures of the drawings.

Referring to the drawings, the numeral 5 designates a fire-alarm box carrying the usual inner casing 6, which contains the main-alarm mechanism, which is set in operation by the depression of hook 7. The main box 5 is provided with the usual door 8, which carries the shunt-pins 9, which serve when said door is closed to shunt the box out of circuit in the usual and well-known manner. Pivoted to the inner casing 6 is a substantially Z-shaped lever 10, which is forced upward against a stop-pin 11 by a spring 12. Secured to the inner face of door 8 is a lock 13, having a longitudinally-movable bolt 14, the keyhole of said lock registering with a keyhole 15, formed in door 8, (see Fig. 1,) whereby the lock 13 is controllable from the exterior of the main box. Pivoted to the outer end of bolt 14 (see Fig. 4) is a cam-knuckle 16, grooved, as at 17, and formed with a working face 18. Said cam-knuckle 16 is normally held in alignment with bolt 14 by a spring 19, one end of which is secured to bolt 14 and the free end of which bears against the rear of the cam-knuckle. Pivoted at 20 to the door 8 is a shaft 21, upon which is mounted a controlling-lever 22. Upon one end of shaft 21 is mounted a cam 23, which bears against and compresses a flat spring 24 when the door 8 is closed. (See Fig. 3.)

When in the position shown in Figs. 1 and 3, lever 22 is locked against movement by a piece of glass or other frangible device 25, which is inserted in slides 26 and 27, slide 27 being secured to lever 22 and slide 26 being secured to a latch 28, which is pivoted at 29 to lever 22 and carries upon its inner end a hook 30, adapted to engage a locking-lug 31, carried by door 8. A flat spring 32 normally tends to hold said latch 28 in engagement with locking-lug 31.

Referring particularly to Fig. 9, it will be seen that slide 27 is grooved for the reception of the frangible device 25 and that said

frangible device is mounted in a bushing 33, which is recessed, as at 34, for the reception of a pin 35. Bushing 33 is fastened to the frangible member, and in placing said member in position pin 35 is placed in recess 34 and the frangible member and bushing are slid into position in the slide 27 until recess 34 registers with a recess 36, formed in said slide, at which time the pin 35 drops into said latter recess, thereby locking the frangible member into position in said slide. If desired, the inspector or other official may remove said frangible member by inserting a small wire or tool in an opening 37, formed in slide 27, and lifting pin 35 until it is free of said slide. It is apparent that the frangible member and its bushing might then be removed.

Mounted upon a saddle 38 or formed integral with said saddle, as desired, is a local-alarm casing 39, in which is mounted a bell 40, adapted to be sounded by strikers 41, mounted upon the striker-arms 42 of a rotating spider, to which motion is imparted by a spring-actuated motor 43, which may be of any desired construction, but is shown in the present instance as comprising a spring 44, a winding-ratchet 45, a large gear-wheel 46, adapted to be driven by spring 44, and a pinion 47, with which said large gear meshes and which is mounted upon a shaft 48 of striker-arms 42. A pinion 49, fast upon a shaft 50 and meshing with gear 46, imparts rotative motion to said shaft 50 and also to a crank-finger 51, carried upon the inner end of said shaft. A trip 52, comprising the rod 53 and the cam-heads 54 and 55, is held when the parts are in their normal position in the position illustrated in Fig. 3 by a pin 56, which is carried by the upper end of the controlling-lever 22 and engages cam-head 55, at which time cam-head 54 lies in the path of movement of crank-finger 51, and thereby prevents rotation of said crank-finger, and consequently of the local-alarm motor.

It is desirable in adding the local-alarm attachment and hook-pulling devices, herein shown and described, to the boxes now in use to attach the local-alarm casing to said boxes with as little change in the structure of the main box as possible. To this end a detent-pawl 57 is pivoted in a cut-away portion of the saddle and local-alarm casing in such manner that the end 58 thereof will drop by gravity into a notch 59, formed in the main box, when the outer curved-over ends 60 of the saddle are slipped over the eaves of the box and the local-alarm casing and said saddle slid into position, as shown in Figs. 1, 2, and 3. To provide readily-obtainable means for fracturing the frangible device which normally locks the main controlling member against movement, a hammer or its equivalent 61 is fastened by a chain 62 to the door of said box.

The operation of the form of the invention just described is as follows: When the door 8 is closed, the free end of the Z-shaped lever 10 rides through groove 17, while at the same time knuckle 16, by virtue of its lateral movement in one direction, gives sufficiently to permit said knuckle to snap past the free end of said lever, and immediately upon so doing spring 19 causes knuckle 16 to resume its normal position in alinement with bolt 14. The working surface 18 of the cam-knuckle now lies over the free end of lever 10 and in such position as to engage and depress said lever when the door of the box is forced open. When said lever is depressed, it strikes and depresses the hook 7 to thereby permit the main alarm to sound. The closing of the door and the placing of the parts in the position illustrated in Fig. 3 causes a pin 65, carried by shaft 21 and engaging a cam-groove 66 of the door-securing bolt 67, to shift said bolt into the position shown in Fig. 6, thereby to hold said door closed. At this time the flat spring 23 is compressed between the inner casing 6 and the face of cam 23. By referring to Fig. 3 it will be seen that the frangible device serves to hold the outer end of latch 28 in its elevated position, and consequently its inner end in engagement with the locking-lug 31. It is manifestly impossible, therefore, for the main controlling member to be moved from its normal position until said frangible device is broken. When it is desired to turn in an alarm of fire, the operator fractures the frangible device 25 by means of hammer 61. He then grasps handle 68 of latch 28 and pulls the controlling-lever outwardly and downwardly. The initial movement of said lever and cam 23 further compresses spring 24. A very slight movement of said lever is required to move bolt 67 far enough to release door 8. Further movement of lever 22, as well as the action of spring 24, will then serve to force the door 8 open far enough to cause cam-knuckle 16, by riding over the free end of lever 10, to depress said lever, and consequently the main-alarm-controlling hook 7. If the operator should now, through ignorance, slam the door to its closed position, the member that has just served to pull the hook would not come in contact with said hook, but would merely slip into position to again repeat the operation. Immediately upon withdrawing pin 56 from its contact with cam-head 55 trip 52 drops from engagement with crank-finger 51 and permits the local alarm to sound, as will be readily understood. If it be desired to permit an inspector or other official to have access to the fire-alarm box without actuating the main alarm, said inspector may insert a key into keyhole 15 and throw bolt 14 into such position that the knuckle 16 will no longer lie in the rear of the free end of the Z-shaped lever 10. If it be desired to lock the

local alarm out of action at the same time, the door of the local-alarm casing may be opened and a pin 69, such as is illustrated in Fig. 5, may be inserted in any one of the recesses 69' formed in the local-alarm motor frame, at which time said pin will lie in the path of movement of the winding-key 70 of said alarm and will thereby prevent said winding-key from turning. Lever 22 may now be pulled down and door 8 opened without sounding either the main or local alarms. By providing a frangible device for normally locking the main-alarm mechanism in motion a person desiring to turn in an alarm over such a device as is herein shown and described is obliged to come to a full stop before said box long enough to break said frangible member, thereby obviating the possibility of some malicious person in a crowd operating the box by a quick and unobserved movement.

By providing a spring which normally tends to force the door open the sounding of the main alarm is rendered certain as soon as the door of the box is released by the initial movement of the lever 22.

By mounting the local-alarm casing directly upon the top of the box and by having a spring-motor for actuating the alarm, said motor being wound independently of the lever 22, said local alarm will continue to sound for a considerable period of time after the movement of said lever has ceased.

By providing the detent connection herein shown and described between the local-alarm casing and the main box it is possible to secure said main-alarm casing to the fire-alarm box without tapping holes for screws or other fastening devices into said fire-alarm box.

In Figs. 10 and 11 a modified form of the device is illustrated. In this instance the local-alarm casing is constructed with an overhanging portion 71, in which is mounted a trip 72, adapted to be engaged by a projection 73 of the door 8' when said door is closed, to thereby hold said trip in its elevated position to arrest movement of the local-alarm motor. A lever 74, secured to a key 75, which controls the lock of the door 8' in the usual manner, is normally locked against movement by a glass 76, which is slipped into a groove of said handle and into a slide 77, carried by the door 8'. The hook-controlling members in this form of the device are the same as those illustrated in the preferred form. A flat spring 78 bears between the inner casing 6 and the door 8' and normally tends to force said door open.

It is apparent that the frangible device herein shown and described may be applied to fire-alarm boxes independently of the hook-pulling devices herein shown and described. It is also apparent that it is not absolutely essential to have a local alarm in

combination with the said frangible device, for it serves its purpose of locking the door-controlling member against movement until it is fractured whether a local alarm be used 5 therewith or not.

If desired, the enlarged end of lever 74 may be of sufficient weight to cause said lever to drop and release the door when the glass is broken. Flat spring 78 would then act to force said door open and set the alarm in motion without any other movement on the part of the operator than the breaking of the glass.

From the foregoing description it will be seen that simple and efficient means are hereinafter provided for accomplishing the objects of the invention; but while the elements shown and described are well adapted to serve the purposes for which they are intended it is to be understood that our invention is not limited thereto, but includes within its purview such minor changes as may be made within the scope of the appended claims.

Having described our invention, what we claim is—

25 1. A fire-alarm box having a door, a lever located upon the exterior face of said door, a main-alarm mechanism, means for setting said main-alarm mechanism in motion when said lever is actuated and a frangible plate 30 one edge of which engages said lever and the other edge of which engages a fixed member carried by the door.

35 2. The combination with a fire-alarm box of a local-alarm casing resting upon said box, the bottom of said casing having an opening formed therein, a detent pawl or latch pivoted in said opening, the lower end of said pawl being adapted to engage a portion of the fire-alarm box and the upper end of said pawl 40 projecting above its pivotal point.

45 3. In a fire-alarm box, the combination with a main-alarm mechanism, of local-alarm mechanism, members engaging and controlling both of said alarms and the door of the fire-alarm box and a frangible device normally locking one of said members against movement.

50 4. The combination with a fire-alarm box, of a hook-pulling member carried by the door of said box, said hook-pulling member comprising a cam-carrying member and a cam pivoted to said cam-carrying member.

55 5. The combination, with a fire-alarm box, of a hook-pulling member carried by the door of said box, said hook-pulling member comprising a cam-carrying member and a cam pivoted to said cam-carrying member and a spring which normally holds said cam in alignment with the cam-carrying member.

60 6. The combination with a fire-alarm box, of a hook-pulling member, said hook-pulling member comprising a cam-carrying member and a cam pivoted to said cam-carrying member and adapted to give in one direction.

65 7. The combination, with a fire-alarm box,

of main-alarm mechanism, local-alarm mechanism, a member controlling said main-alarm mechanism, a lever pivoted for swinging movement adjacent said alarm-controlling member, a cam carried by the door of the fire-alarm box, adapted to engage said swinging lever, a lock for said door and a lever controlling said lock.

8. In a fire-alarm box, the combination with a main-alarm controlling hook or the like, of a member carried upon the inner face of the door of the box and adapted to depress said hook when the door is opened, a door-controlling lever located upon the exterior of the box, a frangible device which prevents movement of said lever until broken, means for automatically forcing said door open when released, a local-alarm bell located upon the top of the box, a spring-motor for sounding said bell, a trip for said motor the lower end of which extends below the top of the fire-alarm box and a member carried by the door and adapted to hold said trip in an elevated position to thereby prevent the local-alarm bell from sounding as long as said door is closed.

9. The combination with a fire-alarm box, of main-alarm mechanism, local-alarm mechanism, members controlling both of said mechanisms, a frangible device normally locking one of said members against movement means for setting the main-alarm mechanism in motion when said last-named member is actuated, and means for throwing both the main and local alarm mechanisms out of action, said main-alarm-controlling member being located upon the exterior of the box and beyond the plane thereof.

10. The combination with a fire-alarm box, of main-alarm mechanism, comprising a hook, a lever pivoted for swinging movement over said hook, means carried by the door of the box for actuating said lever and means controllable from the exterior of the fire-alarm box for withdrawing said actuating means from engagement with said lever.

11. In a fire-alarm box, the combination with a main-alarm mechanism, of local-alarm mechanism, a lever pivoted upon the door of the box and adapted when actuated to operate the main alarm and to release the door of the box and a frangible device which normally locks said lever against movement.

12. In a fire-alarm box, the combination with an alarm mechanism, of an alarm-controlling hook or the like, a member adapted to depress said hook and means carried by the door of the box adapted to snap behind the said member when said door is closed and to actuate said member when said door is opened.

13. In a fire-alarm box, the combination with an alarm-controlling member of means carried by the door of the box for automatically actuating said alarm-controlling mem-

- ber as the said door is opened, said means being so arranged as not to strike said alarm-controlling member when the door of the box is closed.
- 5 14. A fire-alarm box having a door, a lever pivoted for swinging movement upon the exterior of said door, said lever having a groove formed in the under face thereof, and a frangible plate one edge of which engages in said groove and the other edge of which engages a fixed member carried by the door.
- 10 15. In a fire-alarm box, the combination of a main-alarm-controlling hook or the like, means carried upon the inner face of the door of the box for depressing said hook when the said door is opened, means for controlling said hook-depressing means from the exterior of the box to withdraw said means from engagement with the hook, a lever controlling the door of the box, a spring which tends to force said door open, and a frangible device which prevents movement of the door-controlling lever until broken.
- 15 16. In a fire-alarm box, the combination with a main-alarm mechanism, of a local-alarm casing situated upon the top of said box, a bell in said casing, a spring-actuated motor for sounding said bell, members engaging and controlling both the main-alarm mechanism and said spring-actuated motor and a frangible device normally locking one of said members against movement, said latter member being located upon the exterior of the door of the fire-alarm box.
- 20 17. In a fire-alarm box, the combination with a main-alarm mechanism, of local-alarm mechanism, members engaging and controlling both of said alarms, means normally tending to force the door of the fire-alarm box open and a frangible device normally locking one of said controlling members against movement.
- 25 18. The combination with a fire-alarm box, of main-alarm mechanism, a member controlling said mechanism, and means for actuating said member, said means comprising a bolt controllable from the exterior of the box and a cam member pivoted to said bolt and adapted to give in one direction.
- 30 19. A fire-alarm box having a door, a lever controlling said door and having a groove formed therein, a frangible plate, one edge of which engages in said groove and the opposite edge of which engages a fixed member on the door, main-alarm mechanism and means for automatically setting said main-alarm mechanism in motion when said door is opened.
- 35 20. The combination with a fire-alarm box, of a local alarm adapted to be engaged and cut out of action by a projection of the door of the fire-alarm box when said door is closed, a lever controlling said door and a frangible device normally engaging and locking said lever against movement.
- 40 21. The combination with a fire-alarm box, of a local alarm adapted to be engaged and cut out of action by a projection of the door of the fire-alarm box when said door is closed, a member controlling said door and a frangible device normally locking said member against movement.
- 45 22. The combination with a fire-alarm box, of a hook-pulling member carried by the door of said box, said hook-pulling member comprising a key-controlled bolt, a cam pivoted to said bolt, and a spring which normally holds said cam in alignment with said bolt.
- 50 23. The combination with a fire-alarm box, of main-alarm mechanism, a member the movement of which sets said main-alarm mechanism in motion, located upon the exterior of the box, a frangible device normally locking said member against movement and means for locking said frangible device in position.
- 55 24. The combination with a fire-alarm box, of a main-alarm, a local alarm, members engaging and controlling both of said alarms, a frangible device normally locking one of said members against movement and means for normally locking said frangible device in position, said main-alarm-controlling member being located upon the exterior of the fire-alarm box.
- 60 25. In a fire-alarm box, the combination with main-alarm mechanism, of local-alarm mechanism, members engaging and controlling both of said alarms, a frangible device normally locking one of said members against movement, means independent of said controlling member for locking both the main and local alarms out of action and means for locking said frangible device into position, said main-alarm-controlling member being located in a plane beyond and in front of the door of the fire-alarm box.
- 65 26. The combination with a fire-alarm box, of a door, fastening means for said door, a hook-pulling member carried by the door and adapted to give in one direction when the door of the box is closed and means for forcing the door of the fire-alarm box open when its fastening devices are released.
- 70 27. The combination with a fire-alarm box of a member located upon the exterior of said box, main-alarm mechanism, means for setting said main-alarm mechanism in motion when said member is actuated, a frangible device which normally prevents movement of said member and a local alarm adapted to be set in operation when said member is actuated.
- 75 28. The combination with a fire-alarm box having a door, of a door-controlling lever located upon the outer face of said door and locked against movement by a frangible member and means normally tending to force the door of said box open, a main-alarm mechanism and means for setting said main-alarm

mechanism in motion when the door of the fire-alarm box is opened.

29. The combination with a fire-alarm box of a local alarm adapted to be engaged and cut out of action by a projection of the door of the fire-alarm box when said door is closed, a member controlling said door, a frangible device normally locking said member against movement, a main-alarm-controlling member, and means carried by the door of the box for actuating said main-alarm-controlling member when said door is opened.

30. In a fire-alarm box the combination with a main alarm of a local alarm, a lever, a frangible device normally locking said lever against movement and means whereby both the main and local alarms will be set in motion when said lever is actuated.

31. A fire-alarm box having a door-con-

trolling member mounted upon the face of the door of said box and a frangible device which prevents movement of said member until broken but which does not cover said member.

32. A fire-alarm box having a movable member located upon the exterior of said box, means for setting a main-alarm mechanism in motion when said member is actuated and a frangible device which prevents movement of said member until broken but which does not cover said member.

In testimony whereof we affix our signatures in presence of two witnesses.
